UNITED STATES PATENT OFFICE.

NILS SVENSSON BÖK, OF STOCKHOLM, SWEDEN.

CENTRIFUGAL SEPARATOR.

No. 841,370.

Specification of Letters Patent.

Patented Jan. 15, 1907.

Application filed January 7, 1905. Serial No. 240,111.

To all whom it may concern:

Be it known that I, NILS SVENSSON BÖK, a subject of the King of Sweden, and a resident of Stockholm, Sweden, have invented new and useful Improvements in Centrifugal Separators, of which the following is a specification, reference being had to the drawings accompanying and forming a part hereof.

This invention relates to improvements in centrifugal separators having liners dividing the interior of the separating-bowl in thin spaces in which the separation process wholly or partly takes place.

The object of the invention is to introduce the full-milk into the said separating-spaces of the liner in such manner that such proportions of the liquid to be separated will be distributed to the said spaces as correspond to their separating power so as to obtain the highest possible efficiency of the separator.

The invention is especially applicable to the so-called "alpha Laval separators," the distributing means of which heretofore used are, as trials have proved, unsatisfactory.

The method of introducing the liquid to be separated into the thin spaces between the plates of the liner is, according to the present invention, that the liquid to be separated is compelled to pass at suitable speed through one or more, principally axially running, channels the liquid containing cross-sections of which are diminishing in the direction of the flow of liquid, the side of the said channel or channels facing the edges of the liner being open. The liquid to be separated will thereby be compelled to flow out between edges of the plates of the liner that are placed sufficiently near to the open side of the said channels and forming inlet-openings of the separating-spaces. The latter will each receive a certain quantity of the liquid to be separated from the part of the channel situated between the two sections of the channel, the planes of which run through each of two adjacent edges of plates. By determining the average speeds in each of the said sections and the decrease of the one section in relation to the foregoing the quantity of liquid introduced into the corresponding separating-space may be determined.

The energy of translation which the liquid to be separated has while flowing axially in the said distributing channel or channels is partly transferred into pressure in the parts of the liquid received by the inlet-openings, and the said pressure or overpressure over

the static centrifugal pressure in the said openings will cause the introduction of the liquid into the respective separating-spaces.

In the accompanying drawings I have shown a number of devices embodying my invention.

Figure 1 shows a central vertical section of one constructional form of my invention. Fig. 2 shows a horizontal section on line A B in Fig. 1. Fig. 3 shows a central vertical section of a second constructional form, and Fig. 4 a horizontal section on line C D in Fig. 3. Fig. 5 shows a central vertical section of a third constructional form, and Fig. 6 a horizontal section on line E F in Fig. 5. Fig. 7 shows a central vertical section of a fourth constructional form, and Fig. 8 a horizontal section on line G H in Fig. 7.

Like reference characters indicate same or corresponding parts throughout all the figures.

Referring to Figs. 1 and 2, a fluid-leading device 1 is provided in the neck of the bowl A, the said device 1 having in its lower part outlet-channels 2, opening into corresponding channels 3, provided in the central pipe 10. The said channels 3 are continued by distributing-channels 4, open at the sides facing the circumference of the bowl and having their walls facing the axis of the bowl inclined in such manner that the cross-sections of the said channels 4 decrease in the direction of flow, here downward. The edges of the side walls 6 of the said channels 4 bear against the edges 8 of the plates 7, engaging in the usual manner by means of notches the walls 6, while the inner edges 9 of the plates 7 are at such distance from the wall of the central pipe 10 as to leave passages for the separated cream. By giving the channels 1, 2, 3, and 4 suitable cross-sections it will be possible to have the full-milk let into the channel or channels 4 at such a speed that the energy of translation of the quantities of full-milk, detached by the edges 8 at a suitable angle α , transferred into pressure will cause the entrance and distribution of the quantities of full-milk simultaneously in all the spaces between the plates 7 of the liner. By this means a compulsory and, on account thereof, reliable distribution of the full-milk in all the separating-spaces will be obtained.

Referring to Figs. 3 and 4, the bowl is provided with a usual central pipe 10, communicating at the lower end with a usual slime-cup 13. From the latter lead oblique

channels 2, the outlet-openings 3 of which open into the distributing-channels 4, provided in the usual guide-lists 5 on the inner circumference of the bowl 11, the said guide-lists sustaining the outer edges of the plates of the liner. The full-milk let into the upper end 1 of the central pipe 10 falls down into the slime-cup 13 and flows therefrom, through the channels 2 and the outlet-mouths 3, into the distributing-channels 4, the cross-sections of which decrease in the direction of flow—viz., upward. The edges 8 of the plates strike the upward-flowing full-milk at a suitable angle α , and the full-milk will also in this case be compelled to distribute itself uniformly in all the separating-spaces between the plates of the liner. The flanges 12, projecting from the central pipe 10, serve only to sustain the inner edges 20 of the plates 7.

Figs. 5 and 6 illustrate the application of my invention to a well-known so-called "alpha Laval separating-bowl." The usual central pipe 10, which at the lower end communicates with a slime-cup 13, is provided with radially-projecting flanges 5, in which my improved distributing-channels 4 are provided, the said channels 4 communicating with the slime-cup 13 by orifices 2 in the upper part of 25 the latter. The inner edges of the plates 7 bearing against the sides of the channels 4 are preferably bent in such manner that the angle α of the edges 8 and 9 of the plates 7 in relation to the direction of flow in the said 30 channels 4 are more suitable than the angle β formed by the generatrix of the cones with the said direction of flow when the inner edges of the plates are not bent in the said manner. By using a suitable angle α a successive tangential spreading of the full-milk 35 within the thin separating-spaces will be obtained, while an unsuitable angle β causes an abrupt and violent tangential spreading close to the edges 6 of the sides of the channels 4 in disturbing proximity to the cream between the edges 9 of the plates and the outer surface of the central pipe 10. By bending the plates of the liner at a suitable 40 distance from the edges 6 the zone is determined in which the most effective spreading 45 of the full-milk will take place. The full-milk let into the top end 1 of the central pipe 10 will, as usual, fall down into the slime-cup 13 and thereupon rise through the orifices 2 into 50

the distributing-channels 4, from which the full-milk will uniformly enter all the separating-spaces between the plates 7.

In the constructional forms described above the tapering distributing-channels 4 have parallel sides 6, so that the side opening of such a channel facing the edges 8 of the plates 7 is of one and the same tangential width along the whole height of the channel, and the decrease of the cross-sections is only due to the inclination of the wall facing the axis of rotation. It is, however, possible, as is shown in Figs. 7 and 8, to make the radial extension of the said distributing-channels constant if the sides of the latter bearing against the edges of the plates 7 are so arranged that they converge in the direction of the flow. In such case the wall 5, facing the axis of rotation, may be dispensed with, inasmuch as the centrifugal force acting upon the surface of the full-milk (indicated by the dotted line a b in the right-hand channel 4, Fig. 7) in the high speed of rotation used in centrifugal separators is so great that all the surface elements of the liquid, while the liquid fully partakes in the rotation, are approximately at one and the same radial distance from the axis of rotation independent of the speeds at which the liquid flows in axial direction at least within certain limits of the axial speed. The said channels 4 may therefore have the appearance shown in the lower part of Fig. 8. With respect to the strength of the central pipe 10 the said inner wall may preferably, however, only partly be dispensed with.

Having now particularly described my invention, what I claim as new, and desire to secure by Letters Patent, is—

The combination with a separating-bowl having a liner therein consisting of superposed, conical plates, of a distributing-channel extending axially along the edges of the liner-plates and unobstructed at its side toward the liner and having its cross-section decreased in the direction of its length and the direction of the flow of the liquid.

In testimony whereof I have signed my name to this specification in the presence of two subscribing witnesses.

NILS SVENSSON BÖK.
